UNITED STATES PATENT OFFICE.

CHRISTENA KEATING, OF COUNCIL BLUFFS, IOWA.

DESIGN FOR A RABBIT DOLL.

Application filed March 28, 1923. Serial No. 5,617. Term of patent 7 years.

To all whom it may concern:

Be it known that I, CHRISTENA KEATING, a citizen of the United States, residing at Council Bluffs, in the county of Pottawattamie and State of Iowa, have invented a new, original, and ornamental Design of a Rabbit Doll, of which the following is a specification, reference being had to the accompanying drawings, forming a part thereof.

I claim:

The ornamental design for a rabbit doll, as shown.

CHRISTENA KEATING.
